UNITED STATES PATENT OFFICE

FRITJOF FRELIN, OF PHILLIPSBURG, NEW JERSEY, ASSIGNOR TO INGERSOLL-RAND COMPANY, OF JERSEY CITY, NEW JERSEY, A CORPORATION OF NEW JERSEY

FUEL DISTRIBUTOR FOR INTERNAL COMBUSTION ENGINES

Application filed December 5, 1930. Serial No. 500,245.

This invention relates to fuel distributors, but more particularly to a fuel distributor for multi-cylinder internal combustion engines of the solid injection type.

One object of the invention is to effect a uniform distribution of the fuel to the several cylinders of the engine.

Another object is to avoid subjecting large areas of the fuel distributing elements to the heavy pressure of the fuel supply.

Other objects will be in part obvious and in part pointed out hereinafter.

The accompanying drawing is a sectional elevation of a fuel distributor constructed in accordance with the practice of the invention.

Referring more particularly to the drawing, A and B represent walls which may be portions of an internal combustion engine to which the distributor may be applied and C is a casing which may be secured to the wall B in any suitable manner, as by bolts D.

The casing C is provided at its lower end with a projection E having an aperture F, a portion G of which is threaded to receive a bolt H extending through a body J for securing the said body to the extension E. The outer portion K of the aperture F may, as shown, be in the form of a plane cylindrical surface to cooperate with the unthreaded portion of the bolt for assuring concentricity of the body J with the extension E.

Additional means may be provided to assure this assembled relationship of the body J with the extension E, as for instance a bushing L which extends through the body J and is seated in a recess O in the extension E. The bushing L forms a guide for the bolt H and may be tightly fitted into the body J to prevent leakage of fuel along the surface of the bolt H.

Preferably the body J is in the form of a cylindrical plate having a main supply passage P into which fuel oil under pressure may be introduced by a connection Q secured to the body J in any suitable manner and leading from a fuel pump (not shown). The inner end of the supply passage P opens into an annular recess or groove R in the body J and in this instance encircling the bushing L.

From the recess R lead radial passages S,

only one of which is shown, but which may be of a number equal to the number of cylinders T of the engine to which it is intended to supply the fuel.

Near the outer ends of the passages S are apertures U which are threaded at their ends as at V and W to receive plugs X and Y respectively. Between the threaded portions V and W of aperture U is a smooth tapered portion Z to form a seat for a correspondingly tapered valve guide b having a stem c extending through the plug Y and having a shoulder d against which the plug Y acts for pressing the tapered surface of the valve guide b into fluid tight relationship with the wall of the tapered portion Z.

Within the valve guide b is a bore e to accommodate the stem f of a valve g which cooperates with a seat h of the valve guide b adjacent the passage S for controlling communication between the said passage S and a passage j in the valve guide b and the body J. The passage j communicates with the bore e and also with a conduit k leading to a spray nozzle o through which the fuel is injected into the combustion chamber of the cylinder T. The stem f is provided with a reduced portion p adjacent the valve g and around which reduced portion the fuel may flow from the passage S to the passage j.

In order to assure prompt closing of the valve g upon the admission of the fuel to the cylinder T the said valve is provided with a spring q which acts against the valve g at one end and with its other end against the bottom of a recess r in the plug U and into which recess the valve g may extend when open.

The means provided for actuating the valves g to the open position comprises a plate member s disposed in the casing C. The member s is secured to the end of a shaft t extending through the walls A and B and carrying on its opposite end a gear u which, like the member s, may be suitably keyed to the shaft t. Meshing with the gear u is a pinion v which may be carried by a cam shaft w of the engine and whereby the member s may be rotated.

The assembly comprising the shaft T, the

gear u and the member s is provided with frictionless bearings x and y . The outer race of the bearing x is disposed in the gear u and the inner race upon the projecting end of a bushing or sleeve z which encircles the shaft t and extends through the walls A and B . The outer race of the bearing y is seated in the member s while the inner race of said bearing is disposed upon an end of the bushing z projecting below the wall B .

The member s , as will be readily apparent, is thus rotated by the gear v and is provided with a slot 2 wherein is disposed valve opening means shown in this instance as being in the form of a roller 3 which may be journalled on a pin 4 seated in the member s . The roller 3 is so disposed within the member s that a portion of said roller lies beneath the member s to engage tappets 5 seated upon the valve stems f and being guided in aperture 6 in the bottom of the casing C and wherein they may rotate freely. The tappets 5 , like the valves g , are arranged in circular fashion about a common axis and in the plane traversed by the roller 3 . On the ends of the tappets 5 which extend into the casing C are heads 7 having central flat portions 8 over which the roller 3 travels during the unseating of the valves g and the heads 7 which are of frusto-conical shape present inclined surfaces 9 wherewith the roller 3 initially contacts to start the opening movement of the valve g .

In order that the tappets 5 may be conveniently adjusted to vary the duration of the open period of the valves g , said tappets are provided with threaded apertures 10 to receive screws or bolts 11 , the ends 12 of which bear against the ends of the valve stems f . Preferably the bolts 11 are provided with lock nuts 13 for locking the bolts 11 firmly in the adjusted positions.

The operation of the device is as follows: Let it be assumed that fuel under pressure is present in the passages S and that the member s is being rotated in the direction necessary for opening the valves g in their proper sequence and in accordance with the firing order of the cylinders T . The roller 3 will then depress the tappets 5 and consequently the valve g successively in the proper order. Upon the opening of each valve g fuel under pressure will flow through the bore e into the passage j , thence through the conduit k to the spray nozzle o whereby it will be injected into the combustion chamber of the cylinder T .

Whenever it is desired to change the duration of the open period of the valve g , as for instance, to prolong the open period, the screw 11 may be partly unthreaded and again locked firmly in position by the lock nut 13 . This adjustment will cause the tappet to extend a slightly greater distance into the casing C so that the roller 3 may strike the in-

clined surfaces 9 of the tappets at points near the lower edge of the said inclined surfaces and the roller 3 will therefore depress the tappets 5 and the valve g throughout a greater arc of travel of the roller and the period during which fuel will flow from the passages S to the passages j will therefore be somewhat extended.

Conversely, if it should be desired to reduce the fuel admission period, the tappets 5 may be adjusted so that the roller 3 will contact with a small area of the inclined surfaces 9 and the valves g will, in consequence, be held open for a shorter period of time.

In practice, the present invention has been found to be extremely efficient. This is due to the fact that the valve actuating mechanism, such as the roller 3 and the member s whereby the roller is carried and therefore the instrumentalities whereby the member s is supported and rotated, are not exposed across wide areas to the requisite high pressure of the fuel supplied to the cylinders. The only areas subjected to such pressure are the comparatively small areas of the valves g .

I claim:

1. In a fuel distributor, the combination with a body having fuel passages and valves to control the passages, of a casing secured to the body and having apertures in axial alignment with the valves, tappets slideable in the apertures and being revolvable therein, a rotary member in the casing, and a roller journalled in the member and acting upon the tappet for opening the valve.

2. In a fuel distributor, the combination with a body having fuel passages and valves to control the passages, of a casing affixed to the body and having apertures in axial alignment with the valves, tappets slideable in the apertures and being revolvable therein, frusto-conical heads on the tappets presenting inclined and flat surfaces and lying in the casing, a rotary member in the casing, and a roller journalled in the member and rolling over the inclined and flat surfaces for opening the valves and for holding the valves momentarily open.

In testimony whereof I have signed this specification.

FRITJOF FRELIN.
